UNITED STATES PATENT OFFICE

2,534,591

CUTTING SECTION FOR CHAIN SAWS

Grady Oswald Geurian, Bly, Oreg.

Application January 15, 1946, Serial No. 641,291

5 Claims. (Cl. 143—135)

1

This invention relates to new and useful improvements and structural refinements in chain saws, applying particularly to that class of saws in which a power-driven, endless chain is equipped with a plurality of spaced cutting surfaces or cutting edges, which progressively increase the depth of the cut being made.

The cutting edges of saws conventionally employed for this purpose are usually set at a rake, or in other words, they are laterally off-set with respect to their longitudinal travel, in order to obtain greater cutting speed. However the rake frequently causes the sharp cutting edge to catch the side of the cut being made, with the result that the saw, as a whole, is urged from its true cut and the operation becomes uneven and often hazardous.

The saws of conventional design also do not incorporate a provision for governing the depth of cut which is to be taken by the successive cutting edges and the sawing operation frequently becomes interrupted by the breakage of the chain or by overload on the motive power when more than the proper depth of cut is being taken.

It is therefore the principal object of this invention to provide a device of the character herein described, in which the cutting surfaces assume the form of arcuate cutting edges and, in which the main cutting force is concentrated in the downward direction while a portion of said force is equally distributed to the sides of the cut.

A further object of the invention is to provide a cutting section in which a pilot automatically governs the depth of cut being taken.

Another object of the invention is to provide a cutting section which may be easily and conveniently sharpened by a cone-shaped grinder.

An additional object of the invention is to provide a cutting section which may be readily removed from the associated chain for replacement purposes.

An additional object of the invention is to provide a cutting section which incorporates a provision for immediate removal of chips, sawdust, and the like.

Another object of the invention is to provide a cutting section which is of simple construction and which can be economically manufactured in large quantities.

With the above more important objects in view, and such other objects as may become apparent as this specification proceeds, the invention consists essentially of the arrangement and construction of parts as illustrated in the accompanying drawings, in which:

2

Figure 1 is a side elevation of the invention, showing the same partially broken away to reveal its construction.

Figure 2 is an end view thereof, taken in the plane of the line 2—2 in Figure 1.

Figure 3 is a cross-sectional view, taken in the plane of the line 3—3 in Figure 1, and

Figure 4 is a side elevation of the invention, showing the same associated with a saw chain and in readiness for operation.

Like characters of reference are used to designate like parts in the specification and throughout the several views.

Referring now to the accompanying drawings in detail, the invention consists of a body assuming the form of a flat plate 1, formed with a pair of apertures 2. The latter are designed to receive the cross pins 3 of an endless chain 4, whereby the plate 1 is inserted into the length of the chain in substitution for one of the links thereof.

It should be understood that a plurality of cutting sections are in this manner inserted into the length of the chain at suitably spaced intervals, depending upon the hardness of the wood being cut and upon the cutting speed desired. The chain travels in the direction of the arrow 5, in accordance with which, the several components hereinafter described shall be referred to as having a leading and a trailing end.

Depending downwardly from the trailing end of the plate 1 is a cylindrical portion 6 which is disposed in parallel with the chain 4, with the longitudinal axis thereof inclining upwardly from its leading end. The portion 6 is provided with a central, longitudinally extending aperture or bore 7, which terminates in a chamfered portion 8, the latter constituting the surface associated with a cutting edge 9.

It should be noted that the cutting edge 9 is of an arcuate configuration, being formed at the intersection of the surface 8 with the outside wall of the cylindrical portion 6.

Projecting downwardly from the trailing end of the portion 6 is a heel 10 which follows the cutting edge and finishes the cut made thereby.

Depending downwardly from the leading end of the plate 1 is a cylindrical pilot block 11, provided at the leading end thereof with a semi-spherical nose 12. This block is in longitudinal alignment with the afore-mentioned cylindrical portion 6 and the lowermost extremity 13 thereof is positioned somewhat above the lower extremity of the cutting edge 9, as is illustrated by the reference numeral 14 in the accompanying Figure 1.

The lowermost extremity of the edge 9 is on

equal level with the lower edge of the heel 10, as indicated by the reference line 15.

When the invention is placed in operation, the depth of cut being taken will be approximately equal to the dimension indicated by the numeral 14 and the greater portion of the cutting force will be concentrated in a downward direction against the floor 16 of the cut. A smaller portion of the force will be equally distributed along the arcuate sides of the cutting edge, and by virtue of this equal distribution of the cutting force, the cutting section will be urged in a straight line along its intended course.

The sawdust removed during the cutting operation will be disposed of by passing upwardly through the bore 7, thereby preventing the clogging of the saw which was frequently experienced in conventional practice as a result of excessive accumulation of sawdust in the cut.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A cutting section for chain saws comprising, in combination, a plate adapted for insertion between the links of a chain, a cylindrical portion on said plate and having a part projecting in the direction in which the saw is to travel, said portion having an upwardly inclined chip clearance passageway formed centrally and longitudinally therein, an arcuate cutting edge on said cylindrical portion at the end of said passageway adjacent said projecting part, a pilot block on the end of said plate in advance of said cutting edge, and a downwardly extending heel at the trailing end of said cylindrical portion.

2. A cutting section for chain saws comprising, in combination, a plate adapted to constitute one of the links of a chain and formed with a plurality of transverse apertures to receive the cross pins of the immediately adjacent links, a cylindrical portion at the trailing end of said plate with said chain, the longitudinal axis of said portion inclining from the leading end thereof, said portion having a longitudinally extending axial bore, an arcuate cutting edge at the forward end of said cylindrical portion, a heel at the trailing end of said cylindrical portion, a cylindrical pilot block secured to the leading end of said plate, and a semi-spherical nose at the leading end of said block, said block and heel being in the same plane with said cylindrical portion, the pilot block extending to a plane spaced beyond a parallel plane including outer edge portions of the cylindrical portion and heel.

3. A cutting section for a chain saw comprising a generally U-shaped substantially flat plate hav-

ing a bight portion and arms, means in the bight portion for connecting the section to and between links in a chain, a pilot block on the end of the arm disposed in the direction the section is to travel, a hollow cylindrical portion on the end of the other arm, and a heel on the trailing end portion of said cylindrical portion, said cylindrical portion having a sharpened leading edge, the extremities of said guide block and cylindrical portion and heel remote from said bight portion being substantially co-planar with the sharpened edge projecting slightly beyond and between the extremities of said guide block and heel.

4. A cutting section for chain saws comprising, in combination, a body adapted for connection to a chain, a chip clearance hollow cylinder in said body, an arcuate cutting edge at the leading end of said cylinder, and means for guiding said edge and governing the depth of cut thereof, said means comprising a pilot block connected to said body in advance of said cutting edge, and a downwardly extending heel at the trailing end of said cylinder and behind said cutting edge.

5. A cutting section for chain saws comprising, in combination, a vertically disposed plate adapted to constitute one of the links of a chain, a cylindrical portion at the trailing end of said plate as placed in a chain saw, said portion having a longitudinally extending chip clearance bore formed centrally therein, a chamfered portion at the leading end of said bore forming an arcuate cutting edge, and means for guiding said edge and governing the depth of a cut made by the cutting edge comprising a heel at the trailing end of said cylindrical portion, a pilot block having a curved surface and secured to the leading end of said plate, and a nose having a curved surface at the leading end of said plate, said block and said cylindrical portion and said nose being all on one side of a chain wherewith the device is used.

GRADY OSWALD GEURIAN.
